UNITED STATES PATENT OFFICE.

WILLIAM H. DEWAR, OF NEW YORK, N. Y.

DESIGN FOR A NOZZLE.

SPECIFICATION forming part of Design No. 33,171, dated September 4, 1900.

Application filed July 14, 1900. Serial No. 23,682. Term of patent 7 years.

To all whom it may concern:

Be it known that I, WILLIAM H. DEWAR, a citizen of the United States, and a resident of the city of New York, borough of Manhattan, 5 in the county and State of New York, have invented and produced a new and original Design for a Nozzle, of which the following is a specification, reference being had to the accompanying drawings, forming a part 10 thereof, in which—

Figure 1 is a side elevation of a nozzle embodying the features of my design, and Fig. 2 is a plan view of the same.

The design relates to nozzles for drinking- 15 fountains.

The design consists of a head A, which is exteriorly conical and provided at its apex with an opening B. At the base portion of

the conical head A a grip D extends upward and outward, while below the base and apparently integral therewith a sleeve B' is formed, appearing circular in general contour. In the formation of the head the side surfaces are drawn upon well-defined convexed lines.

Having thus described my invention, I 25 claim as new and desire to secure by Letters Patent—

The design for the nozzle herein shown and described.

In testimony whereof I have signed my 30 name to this specification in the presence of two subscribing witnesses.

WILLIAM H. DEWAR.

Witnesses:

J. FRED. ACKER,
THOMAS J. FITCH.
